UNITED STATES PATENT OFFICE.

JOSEPH R. VALENTINE AND ALEXANDER T. GRIGG, OF PUEBLO, COLORADO,
ASSIGNORS TO THE VALENTINE & GRIGG MOTOR COMPANY, OF SAME
PLACE.

RAILWAY-MOTOR.

SPECIFICATION forming part of Letters Patent No. 400,522, dated April 2, 1889.

Application filed April 23, 1888. Renewed December 19, 1888. Serial No. 294,117. (No model.)

To all whom it may concern:

Be it known that we, JOSEPH R. VALENTINE and ALEXANDER T. GRIGG, citizens of the United States, residing in the city of Pueblo, in the county of Pueblo, in the State of Colorado, have invented a new and useful Railway-Motor, of which the following is a description.

The invention relates to that class of railway and other vehicles which receive locomotion from an engine which is located upon the vehicle itself.

The leading object of the invention is the provision of means whereby, when the engine is in operation, the vehicle may be instantly arrested in its progress when in motion, or instantly set in motion when at rest without arresting or retarding the movement of the engine or in any way modifying its action.

The invention consists in the combination, with a vehicle which has two or more pairs of supporting-wheels and an engine mounted upon the vehicle of a pair of driving-wheels which are operated by such engine, and a means whereby the driving-wheels may either be instantly brought into contact with the earth or with a track-rail to impart motion to the vehicle, or whereby, when in contact, such contact may be instantly discontinued to terminate the effective action of the impelling power.

The invention consists, also, in the connection of the driving-wheel-operating mechanism with the brake-operating mechanism, whereby the brakes are operated by the same mechanism by which the driving-wheels are held in operative contact with the rail or with the roadway, or are withdrawn therefrom.

The invention consists, also, in other novel parts or combinations of parts, as will be hereinafter described, and then distinctly claimed.

In the drawings, Figure 1 represents a side elevation of a street-railway car, portions being broken out, which is provided with our improved means of propulsion. Fig. 2 is a top plan view, the body of the car and the brake-shaft and its support having been removed.

Fig. 3 is a perspective elevation looking from the front toward the end of the car. Fig. 4 is

a detail face view, drawn to an enlarged scale, of the bearing-plate and its sliding link. Fig. 5 is a section on the line xx of Fig. 4. Fig. 6 is a detail vertical section on the line yy of Fig. 1.

As seen in Fig. 1, the engine B, which may be of any suitable or preferred construction, is by preference located upon the front portion of the car A, which is provided with front and rear supporting-wheels, ww' , of any suitable kind.

Upon each side of the car a bearing-plate, C', having a perforated upper extension, c' , and a bifurcated lower extension, c , is secured to an exterior longitudinal sill, C, of the bed-frame. The lower extension, c , receives within the jaws $c^2 c^2$ of its bifurcated portion the body of a sliding link, d, within the opening of which is received the upper and lower members, $c^3 c^4$, respectively, of a journal-box, C³, which members have in their coincident faces curved recesses, as shown, to receive the end e' of the axle E⁴ of the driving-wheels E. The coincident faces of the jaws $c^2 c^2$ and the corresponding surfaces of the journal-box are slightly curved, as seen in Fig. 4, in the arc of a circle of which the engine-shaft is the center. The link d is provided upon its inner and upon its outer face with washers or guides d', which are secured by screw-bolts d^6 , the washers projecting beyond the body of the link and overlapping each side of the jaws c^2 , as seen in Figs. 4 and 5. The members of the journal-box extend at their ends somewhat beyond the faces of the link in which they are held, and are provided with flanges $c^5 c^6$, which embrace the body of the link.

A spring, d², composed of rubber or other suitable material, is secured by pins $d^4 d^5$, or other means, within the space between the journal-box C³ and the base d³ of the link. A truss-bar, C⁴, which extends across the lower extremity of the bearing-plate C' and is made fast by its ends to the sill C, serves to give increased firmness to the bearing-plate and the wheel-operating mechanism connected therewith.

The upper extremity of the sliding link d is connected by a pivot-joint, d⁷, with the lower

member, f , of a toggle-lever, F, the upper member, f' , of which is secured by a pivot-pin, f^2 , to the upper extension, c' , of the bearing-plate C'. An actuating-lever, J, having its fulcrum 5 j upon the bed-frame of the vehicle, is pivoted at its lower extremity to a connecting-bar, I, which in turn is pivoted to a fixed arm, h, which projects obliquely downward from the transverse rocker-shaft H, which has its 10 bearings in journal-plates h', which are secured to the longitudinal sills C. A fixed upper arm, h^2 , upon the rocker-shaft H, projects in a direction from such shaft opposite to that of the lower arm, h, and at its upper extremity 15 is pivoted to a bar, G, which extends along the sill C and the bearing-plate C', and is received by its opposite end upon the pivot-pin f^3 , which connects the members $f f'$ of the toggle-lever F. Each driving-wheel E has 20 upon its outer face a circular grooved bearing or chain wheel, E', which receives motion from the shaft b of the engine B through the medium of the endless chain K.

It will be observed that the driving-wheels 25 have a broad periphery, to permit free lateral movement in rounding curves without liability to derailment. As shown, these wheels are unflanged; but a flange may be employed when desired.

30 In the operation of the raising and lowering mechanism, which will be readily understood from its representation in Fig. 1, the effect of the downward and forward inclination of the ways in which the link d slides is 35 to cause the driving-wheels to be engaged by a wedge-like action between the track and the car, the engagement being the more positive as the weight of the car or of its load is increased. In their elevated position the driving-wheels are preferably but about one inch 40 from the track-rail, and as the springs of the supporting-wheels $w w'$ have a maximum compressibility of only three-fourths of an inch it follows that the driving-wheels cannot, when 45 elevated, be brought into contact with such rail by any jolting movement of the car. When the lever J is released, the driving-wheels, by their own gravity, descend upon the rail, when a very slight forward movement of such lever renders the engagement of 50 the wheels with the rail rigid and effective for all purposes. The inclination of the ways or jaws similarly operates, when the lever J is thrown backward, to facilitate the elevation of the driving-wheels.

The lever J, which, as already described, is connected by a series of arms, bars, and levers with the wheel-carrying link d, is connected also by a chain, l', with a link, l'', of the brake-chain l, so that when the lever J is thrown forward to thrust the driving-wheels downward upon the track the brakes L are by the same movement of the lever released from engagement with the supporting-wheels $w w'$, and so that when the driving-wheels are lifted 60 such brakes will by the same movement be again brought into contact with such supporting-wheels. It will thus be seen that under this construction both the driving-wheels and the supporting-wheels may be wholly 65 controlled by a single operator.

Having described our invention, we claim—

1. The combination, with a car, of an engine which is fixed upon the car, a pair of driving-wheels mounted in the frame of the 75 car impelled by such engine and movable in ways which are concentric with the axis of the engine-shaft, and a compound lever operable from the engine-platform either to lift the wheels from the track or to hold them in 80 positive and rigid engagement therewith.

2. The combination, with a car, of an engine mounted upon such car, a pair of driving-wheels mounted upon such car and adjustable up or down in ways thereon, a connection between the driving-shaft of the engine and the axle of the driving-wheels, and a lever whereby the driving-wheels are movable either into or out of engagement with the 85 car-track.

3. In a car which is provided with a brake-rod and with brake-chains and brakes, the combination of driving-wheels, an engine, a lever which is operable to adjust such wheels either upon or away from the track, and a chain which connects such operating-lever with the brake-chains, whereby both the driving-wheels and the supporting-wheels are 90 controlled by a single operator.
